CONTROL SYSTEM FOR GUN-MOUNTINGS AND OTHER MECHANISM.

1,211,418.

Specification of Letters Patent.

Patented Jan. 9, 1917.

Original application filed July 12, 1912, Serial No. 708,964. Divided and this application filed December 2, 1913. Serial No. 804,165.

To all whom it may concern:

Be it known that we, ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to Control Systems for Gun-Mountings and other Mechanism, of which the following is a specification.

This invention relates to control systems for gun mountings and other mechanism.

In control systems "hunting" gear has been employed in conjunction with a power driven member forming part of the mechanism to be driven, and with a member which is actuated electrically from a distance but is incapable of itself exerting any appreciable force beyond that which is necessary to operate a relay for bringing the motive power into action. When the electrically actuated member is moved out of alignment or coincidence with a neutral point on the other or power driven member, an electric circuit is closed through suitably arranged contacts forming part of the two members and energizes the relay which brings into operation a motor for driving the mechanism and the said power driven member, such operation continuing so long as the circuit remains closed *i. e.* until the neutral point of the power driven member regains its position of alignment or coincidence with the electrically actuated member.

According to this invention the contact rings on the power member or members are divided into a number of segments each of which is electrically connected to a contact finger or the like that is adapted to bear on one or other of two contact plates connected to the control device, the said contact plates forming part of the electrical connections with the relay.

In order that the said invention may be clearly understood and readily carried into effect we will describe the same more fully with reference to the accompanying drawings, in which:

Figure 1 is a sectional elevation showing a form of the apparatus; Fig. 2 is a diagram showing the electrical connections of the arrangement illustrated in Fig. 1; and Fig. 3 is an enlarged view of the epicyclic gear shown in Fig. 1.

A is the power driven member connected to a toothed wheel A' forming part of the gearing connected to the mechanism to be driven. This mechanism may be the elevating or training mechanism of a gun and in this case the said toothed wheel is driven by an elevating or training hydraulic motor whose control valve is indicated at C in Fig. 2.

Two switches (one of which transmits large increments of range or bearing as set forth for example in the specification of the British Patent No. 11019 of 1911) are used at the transmitting station, and two motors B^x, B^{xx}, at the receiving station, connected to the spindles of members B, B^o. Of these the motor B^{xx} and the member B^o appertain to the switch transmitting the larger increments. In the example shown, the member A is in the form of a drum or disk having on its face two circles of contact segments.

The outer circle of segments a', a², a⁶, a⁷ and a⁸ appertains to the contact b'^x of the member B and the inner circle a⁴, a⁵ appertains to the contact B^o. The contacts b^x and B^o of the members B and B^o respectively bear against a supply ring a³. The contacts shown to the rear of the drum A in Fig. 1 are for the purpose of conveying electric current to the segments.

The motor B^x that appertains to the switch transmitting the smaller increments of range or bearing directly displaces the faster member B through the inner spindle b^o. The motor B^{xx} which moves more slowly than the motor B^x and appertains to the switch transmitting the large increments of range or bearing operates upon the slow moving member B^o through the epicyclic gearing shown clearly in Fig. 3. This gear comprises a sun wheel b^{2x} formed on the spindle B' driven by the motor B^{xx} and toothed wheels a⁹, a^{9x} mounted on a spindle

carried by the drum A; these toothed wheels are integral with one another. The wheel a^9 gears with the sun wheel b^{2x} and the wheel a^{9x} with a toothed wheel b^{2xx} connected to the member B^o. The effect of this differential gearing is to produce a definite angular relationship between the members B, B^o, this angular relationship depending upon the amount of the range or training 10 which is being transmitted. When the drum A is moved by the gun in taking up the position predetermined by the movements of the members B, B^o, it carries with it the toothed wheels a^9 , a^{9x} and as the wheel b^{2x} 15 is now stationary, the movement of these wheels about the axis of the drum causes them to also move about their own axis and thereby displace the member B^o, eventually moving this member into alignment with 20 the member B which remains stationary during this operation; when the members are in this position, the gun is brought to rest as will be more fully described with reference to Fig. 2. When the gun is being elevated or trained quickly the step-by-step motor B^{xx} geared to the outer spindle B' formed with the sun wheel b^{2x} (which motor appertains to the transmitting switch that is adapted to transmit large increments 25 of range or bearing) alone moves and causes a displacement of the slower member B^o which in turn causes the hereinafter described relay to operate and cause the drum A to be angularly displaced an amount corresponding to that of the sun wheel b^{2x} . The stem c of the aforesaid control valve C carries a piston c' disposed in a cylinder d^x having a plug d' by which motive fluid can be admitted to or exhausted from the end 30 of the cylinder remote from the control valve. This plug has a pinion which meshes with rack teeth on the armature or core D^x of two electromagnets or solenoid coils D, D'. The end of the cylinder nearest the 35 valve C is supplied with motive fluid under constant pressure. It will thus be seen that in accordance with the direction in which the armature or core D^x is displaced, the plug valve d' is moved to place the rear end 40 of the cylinder to pressure or to exhaust, thereby causing a movement in one or other direction of the control valve C.

Contact plates C^x, C^{xx} are formed on an extension of the valve stem c and are in contact with fingers c^x , c^{xx} which are respectively connected to the solenoids D, D'. The segments a' , a^2 , a^4 , a^5 , a^6 , a^7 , and a^8 , are in electrical connection with fingers a'^{xx} , a^{2xx} , a^{4xx} , a^{5xx} , a^{6xx} , a^{7xx} , and a^{8xx} respectively, that 45 are adapted to engage with the contact plates C^x, C^{xx}. The supply ring a^8 is connected to the source of electric supply. When the member B moves with respect to the drum A, it causes for example the segment a^6 to be electrically connected with the

supply ring a^8 . The solenoid D will accordingly be energized, and the valve C will be moved until the finger a^{6xx} appertaining to the segment a^6 comes opposite the gap between the two contact plates C^x, C^{xx}. As 70 the drum A moves to assume its original or neutral position with respect to the member B and the contact a^8 becomes electrified, the valve will move until the gap between the plates C^x, C^{xx} rests upon the corresponding 75 contact a^{8xx} and will then be completely shut off and the parts brought to rest.

If the movement of the member B is greater than that above mentioned, it will pass on to the segment a' , and the solenoid 80 D will move the valve C until the gap comes beneath the finger a'^{xx} . If the movement of the member B is greater than half a revolution the member B^o will take over the control, this member being moved by the aforesaid epicyclic gearing into contact with the segment a^5 . The valve C will then be moved until the aforesaid gap comes opposite the finger a^{5xx} , the valve being then fully opened. When the drum A moves as a result of the 90 displacement of the hydraulic motor, the converse operations will take place, that is to say, the valve will be moved intermittently until its closed position, first until the gap between the plates C^x, C^{xx} comes opposite the 95 finger a^{1xx} , then until the said gap comes opposite the finger a^{0xx} and finally until the gap comes opposite the finger a^{8xx} when the valve will be in its closed position and the parts are all at rest. By a suitable separation of the contact fingers, the valve opening 100 may be easily adjusted in proportion to the amount of lag represented by the particular segment in connection with the contact finger. The action of the parts is intermittent 105 in character owing to the number of partial opening and closing movements of the control valve being limited to the number of contact segments. When only one motor is used the member B^o and its circle of segments need not be employed. In this case the teeth of the wheel b^{2x} are formed on the spindle b^o carrying the member B.

What we claim and desire to secure by Letters Patent of the United States is:—

1. In a control system for power driven mechanism, the combination of a member driven thereby, two sets of contact strips and a supply ring thereon, two members actuated from a distance and moving at different speeds, a relay under the control of said members, a control device for the power driven mechanism, means for operating said control device from the relay, means whereby relative movement between said power driven member and said members actuated from a distance renders the relay operative and means whereby the movement of said relay consequent on its being rendered operative, renders it again inoperative.

2. In a control system for power driven mechanism, the combination of a member driven thereby, two sets of contact strips and a supply ring thereon, two members actuated from a distance and moving at different speeds, contact fingers in electrical connection with said strips, contact plates against which said fingers bear, a relay in electrical connection with said contact plates, a control device actuated by said relay, and means for connecting said plates with the control device.

In testimony whereof we affix our signatures in presence of two witnesses.
